BERNARD BIEHL, SR., OF NEWARK, NEW JERSEY, ASSIGNOR TO J. L. SOMMER MANUFACTURING CO., A CORPORATION OF NEW JERSEY.

KEY CASE.

1,418,059.

Specification of Letters Patent. Patented May 30, 1922.

Application filed September 2, 1921. Serial No. 497,927.

To all whom it may concern:

Be it known that I, BERNARD BIEHL, Sr., a citizen of the United States, and a resident of Newark, in the county of Essex and State 5 of New Jersey, have invented new and useful Improvements in Key Cases, of which the following is a specification.

This invention relates to key cases, and more particularly to key cases of the type 0 embodying a flexible folding case similar to a pocket book and having at one end a plurality of pivotally mounted members for holding keys whereby the keys can be positioned within the case or swung outwardly 15 therefrom into position to be inserted into a lock.

The objects of the invention are to provide a key case of the character described in which the pivotally mounted members for holding the keys are formed of an anchor member and a clip pivoted thereto; to thus enable the desired restriction of movement of the anchor member with respect to the case to be secured and yet the key receiving 25 clip have a greater freedom of movement; to thus facilitate the handling and operation of a given key when projected from the key case, so that it can be used more conveniently; to make the anchor member only long 30 enough to project from the key case and the key receiving clip longer so as to secure freedom of the key with respect to the case at a point at or near the edge of the case, and to obtain other results and advantages as may 35 be brought out by the following description.

Referring to the accompanying drawings, in which like numerals of reference indicate the same parts throughout the several views,

Figure 1 is a plan view of the key case 40 constructed in accordance with my invention, showing the same open with the key holding means in normal position;

Figure 2 is an enlarged fragmentary sectional view through the pivot tube of the 45 holding strip, showing one key holding member in normal position within the case and one swung into operative position out of the case;

Figure 3 is a fragmentary longitudinal 50 sectional view through the body portion of the case and the holding strip, taken on the line 3-3 of Figure 2, one of the key holding members being shown in side elevation;

Figure 4 is transverse sectional view

through the pivot tube taken on the line 55 4-4 of Figure 2;

Figure 5 is a detached perspective view of one of the anchor members, and

Figure 6 is a fragmentary perspective view of the key case and a key in a lock 60 showing the operation of the device.

In the embodiment of the invention shown in the drawings, the reference character A designates the case which comprises a single piece of suitable material, preferably flexible 65 such as leather, adapted to be folded on the lines 1, 1 to form a body portion 2 and co-operating closure flaps 3. The flaps 3 are adapted to be folded over the body portion 2 in overlapping relation and to be secured 70 to each other by any suitable means such as the head and socket fastening members 4 and 5 secured respectively to the flaps 3.

A metal holding strip 6 is secured by suitable means, such as the eyelets 7, to the body portion 2 of the case adjacent one end thereof, the said strip having one edge thereof rolled backwardly upon itself to form a pivot tube 8 which is formed with a plurality of 75 transverse slots 9 spaced longitudinally of the tube. The slots 9 are preferably formed in the strip before the same is rolled into the tube 8, and with reference to Figure 3 of the drawings it will be noted that said slots terminate short of the edge of the strip so as to 80 provide connecting portions 10 between opposite sides of the slots at the inside of the tube.

An anchor member 11 is pivotally and 85 swivelly mounted in each of the slots 9, the 90 said members comprising shanks of a diameter slightly less than the width of the slot 9, and having at one end thereof substantially spherical heads 12 of a diameter less than the diameter of the tube and greater than 95 the width of the slots 9, said heads being arranged within the pivot tube 8. The opposite ends of the members 11 are preferably flattened as at 13, and are formed with openings 14 to pivotally receive key holding clips 100 15 which are adapted to receive keys 16 shown in dotted lines on Figure 1. In applying the anchor members 11 to the pivot tube 8, the edge of the strip 6 is partially returned upon itself, after which the shanks 105 of the members 11 are passed outwardly through the slots 9 between the body portion of the strip and the returned edge thereof.

The edge is then completely returned upon the strip so as to enclose the heads 12 of the anchor members within the pivot tube 8. With this construction it will be observed that the anchor members are adapted to swing through the slots 9 in single plane longitudinally of the body portion 2 of the case, and are also adapted to revolve about their axes independently of the case and strip 6.

In normal operation of the device the anchor members 11 and clips 15 are swung against the body portion 2, as shown in Figure 1, and the keys 16 carried by the clips 15 lie substantially flat against the said body portion. The closure flaps 3 are normally folded over the keys and anchor members and fastened together, thereby preventing the anchor members from swinging out of the case or moving longitudinally outwardly through one end thereof. The engagement of the shanks of the anchor members with the edges of the slots 9 limits lateral movement of the anchor members so that the keys do not become tangled and yet the clips pivoted to the anchor members permit great freedom of movement of a single key when it is projected from the key case. When it is desired to use one of the keys for operating a lock, the flaps 3 are unfastened and the desired key swung out of the case into the position shown in Figures 2 and 6 and by dot and dash lines in Figure 3, outward movement of the anchor 11 being limited by the end of the slot 9. The key may then be revolved in the lock, and the swivel connection of the anchor member with the pivot tube 8 enables this revolution of the key without rotation or other movement of the case. The clips 15 provide a flexible connection of the keys to the case and enable the key to be swung a sufficient distance out of the case to facilitate free operation of the key in a lock, the said clips, when the keys are in the case and the flaps 3 fastened together, also being sufficiently rigid to prevent the keys from sliding out through the end of the casing. It will be noted that not only can the anchor members 11 swing and turn with respect to the key case, but the clips 15 are also pivoted to the anchor members as well as to the case. A very flexible connection of the key to the key case is thus provided, which greatly facilitates convenience and natural use of a key. For example, when the key is grasped for use the key clip is naturally grasped also and may by my improved construction be held practically against movement with respect to the key, the pivotal movement necessary for the key with respect to the key case taking place at the ends

of the anchor member. Furthermore, it will be noted that the clips 15 are preferably longer than the anchor members 11, 61 said anchor members serving chiefly to extend over the edge of the key case and locate the pivotal connections of them to the key clips outside the key case. This secures the flexibility in use which has been described, and yet at the same time sufficiently confines the keys when the case is closed, as has also been explained.

Obviously modifications or changes may be made in the detail construction of my invention without departing from the spirit or scope thereof, and therefore I do not desire to be understood as limiting myself except as required by the following claims when construed in the light of the prior art.

Having thus described the invention, what I claim is:

1. A key case including a tubular support having a transverse slot therein, an anchor member having a shank passing into said tubular support through said slot and a head on the end thereof arranged within said tubular support of a diameter greater than the width of said slot, whereby said anchor member can swing in said slot and revolve about its own axis relatively to said tubular member, and a key receiving clip pivotally connected to the other end of said anchor member.

2. A key case including a tubular support having a transverse slot therein, an anchor member mounted to swing in said slot and revolve about its own axis relatively to said tubular member, and a key receiving clip pivotally connected to the other end of said anchor member.

3. A key case including a tubular support having a transverse slot therein, an anchor member having a shank passing through said slot with a head in the tubular support 105 and an eye at its outer end, and a key receiving clip hinged in said eye.

4. A key case including a tubular support having a transverse slot therein, an anchor member mounted to swing in said slot, 110 and a key receiving clip of greater length than said anchor member pivotally connected to the end of the same away from the tubular support.

5. A key case including a tubular support 115 having a transverse slot therein, an anchor member having a shank passing through said slot with a head in the tubular support and an outer end flattened to a width greater than that of said slot and perforated, 120 and a key receiving clip hinged in said perforation.

BERNARD BIEHL, SR.
